UNITED STATES PATENT OFFICE.

CHESTER MCNEIL, OF CHICAGO, ILLINOIS, ASSIGNOR TO THE UNION SPECIAL SEWING MACHINE COMPANY, OF CHICAGO, ILLINOIS, A CORPORATION OF ILLINOIS.

SEAM FOR SEWED ARTICLES.

SPECIFICATION forming part of Letters Patent No. 718,654, dated January 20, 1903.

Application filed January 12, 1900. Serial No. 1,177. (No model.)

To all whom it may concern:

Be it known that I, CHESTER MCNEIL, a citizen of the United States, residing at Chicago, in the county of Cook, State of Illinois, have 5 invented certain new and useful Improvements in Seams for Sewed Articles, of which the following is a description, reference being had to the accompanying drawings and to the letters and figures of reference marked 10 thereon.

My invention relates to an improvement in seams for sewed articles; and the object is to provide a combination of ruffled fabric and stitches when the stitches which secure the 15 folds of the fabric are not visible, but only pass through the base of the ruffles, after which the ruffled piece may be secured to another fabric, or the same stitches which set the ruffles may be used to unite the ruffled 20 piece to the goods forming the body.

Heretofore in the operation of sewing and ruffling the ruffler-blade gathers the goods and a row or rows of stitches are passed entirely through the ruffles, thus showing on both 25 sides. The idea of the present invention is to avoid entirely the appearance of threads upon the upper surface of the fabric and simply to sew through the ruffles at the base, thereby enabling the ruffles to stand out 30 straight and not be sewed down flat, as is customary.

The invention therefore consists of a fabric having a series of ruffles or gathers, means for securing the bases of said ruffles or gathers comprising locking - threads passing 35 through said bases and properly secured, leaving the tops of the ruffles free and open, with no stitches passing over said tops.

The invention is illustrated in the accompanying drawings, in which—

Figure 1 is a front perspective view of a ruffed fabric made in accordance with my invention. Fig. 2 is a rear perspective view of the same. Fig. 3 is a rear perspective view 45 showing the combination of ruffled fabric, stitches, and backing fabric; and Fig. 4 is an enlarged perspective view illustrating the ruffled fabric and the stitches securing the same.

50 In the drawings, A represents a piece of

fabric provided with ruffles or gathers, and, as shown in Figs. 2 and 4, these ruffles or gathers are secured in place by means of stitches in which the needle-threads 1 pass substantially horizontally through the base 55 of the ruffle, into and out of the same, and are secured by looper-threads 2. Thus the ruffles are not sewed through and through down to the body of the fabric, as is usually the case; but the stitches pass only through the 60 base of the ruffles, and thus the latter may stand out from the body of the fabric, no stitches showing on the upper surface of the fabric.

In Fig. 3 the ruffled fabric A is shown as 65 secured to a second piece of fabric B, which may be the body of a skirt or other garment, and in this arrangement the threads 1 pass into the fabric B, through the base of a ruffle a, and thence out again through the fabric 70 B, there being secured by the threads 2, as shown.

The operation of sewing and ruffling to make this seam is preferably performed upon a sewing-machine having a mechanism for 75 ruffling the piece of goods A and feeding it to a stitch-forming mechanism, which deposits stitches therein in the manner indicated.

Having thus described my invention, what I claim, and desire to secure by Letters Patent, is—

1. As a new article of manufacture, a fabric having a series of ruffles or gathers, and means for securing the bases of said ruffles or gathers, comprising locking - threads passing 85 through the bases of said ruffles or gathers, and between consecutive bases passing beneath the opposite faces or tops of said ruffles or gathers, whereby said tops are left free and open and the stitches are concealed; substantially as described.

2. As a new article of manufacture, a fabric having a series of ruffles or gathers, a body fabric, and means for securing the ruffed fabric to the body fabric, said means comprising locking-threads passing through the bases of said ruffles or gathers and through the body fabric, and between consecutive bases passing beneath the opposite faces or tops of said ruffles or gathers, whereby said 95 100

tops are left free and open, and the stitches are concealed; substantially as described.

3. As a new article of manufacture, a fabric having a series of ruffles or gathers, combined with threads passing through the bases of said ruffles or gathers, and entering and emerging upon the same face of the fabric, with means for securing said threads upon the same face on which they enter and 10 emerge, whereby the tops of said ruffles or gathers are left free and open; substantially as described.

4. As a new article of manufacture, a fabric having a series of ruffles or gathers, a second

fabric combined with a series of threads passing into and out of the second fabric, entering and emerging on the same face, and engaging the bases of the ruffles, with means for securing said threads, whereby the tops of said ruffles or gathers are left free and open; 15 substantially as described.

In testimony whereof I affix my signature in presence of two witnesses.

CHESTER McNEIL.
